DRIVE LUG FOR PILOT BIT AND EARTH BORING AUGERS

Gerald A. M. Petersen, Santa Clara, Calif.

Application November 15, 1954, Serial No. 468,620

9 Claims. (Cl. 255—61)

This invention relates to earth boring tools or augers and more particularly to drive lugs for that portion of the tool which encounters the earth first, commonly referred to as a pilot bit.

The present invention relates to certain novel improvements in the drive lug or coupling of the pilot bit to a drive or auger shaft in the manner as generally shown in my co-pending application Serial No. 414,007, filed March 4, 1954, now Patent No. 2,773,673, in the United States Patent Office.

It is an object of this invention to provide a simple drive lug for adapting a drive shaft to receive a pilot bit.

Another object is to provide a drive lug so constructed as to effectively absorb the reacting forces to which it is subjected while in driving relation with a pilot bit.

Another object is to provide means for coupling a pilot bit to a drive shaft or auger in a manner to provide continuous upward flow of spoil. In this connection it is a further object to provide a coupling media with a passage system communicating a fluid carrying bore in a drive shaft with discharge ports in the region of boring of the pilot bit.

Yet another object is to provide a coupling means in the form of a drive lug conforming with the contour of a pilot bit body in a manner to generate a maximum of driving energy between a drive lug and pilot bit with a minimum of weakening of the assembly so constructed. In this connection it is an object to provide a drive lug having a diametrically extending key portion flanked by partial ear portions in a leading direction with respect to the direction of turning of the drive lug. The object of this construction is to effect a minimum of counter-forces on the leading or driving faces of the key and ear portions of the drive lug so as to obtain a maximum of dynamic efficiency.

These and other objects and advantages of the present invention will become more apparent from a reading of the following description when taken in the light of the drawings in which:

Fig. 1 is an elevation of a drive lug secured to a drive shaft in accordance with the present invention.

Fig. 2 is an enlarged top plan view of a pilot bit adapted for receipt of the drive lug of Fig. 1.

Fig. 3 is a bottom plan view of the drive lug of Fig. 1 and complementary to, and adapted to be received in the pilot bit of Fig. 2.

Fig. 4 is an enlarged elevational view of the drive lug in Fig. 1 and the pilot bit in Fig. 2 assembled and partly broken away for purposes of illustration.

Fig. 5 is a horizontal section through the assembly of Fig. 4 taken along line 5—5 thereof.

Figs. 6 through 9 inclusive show an assembly similar to the one illustrated in Figs. 1 through 5 but modified in a manner to provide passage of fluid through the assembly. In this connection, Fig. 6 is a top plan view of the pilot bit of Fig. 2 so modified.

2

Fig. 7 is an enlarged elevation similar to that of Fig. 4 partly broken away to illustrate the communication of fluid passages through the several parts thereof.

Fig. 8 is a fragmentary elevation taken from the same angle as that of Fig. 4, also illustrating the communication of fluid passages.

Fig. 9 is a horizontal section through Fig. 7 taken substantially along line 9—9 thereof.

Fig. 10 is a perspective view of a modified form of the drive lug shown in either Figs. 1 through 5 or 6 through 9.

Fig. 11 is a section through Fig. 10 taken at line 11 thereof.

The coupling means 10 of the present invention consists of a drive lug 11 for connecting a pilot bit 12 to a drive shaft 13. For purposes of clarity and in order to distinguish between the different forms of the drive lug and associated parts, whole numbers, such as 10, 11, 12 and 13, will be used in explaining Figs. 1 through 5, as well as Figs. 10 and 11, while similar numerals with prime exponents will designate like parts in Figs. 6 through 9.

At the outset it should be understood that the coupling means 10 or 10' embodying the present invention contemplates the use of a pilot bit 12 or 12' having a central body portion 14 or 14' of sufficient girth to accommodate the drive lug 11 or 11'. For example, the main body or central core of the pilot bit should be enlarged at its base or upper end and gradually taper toward its opposite end, or, be preferably of cone shape as illustrated and as more particularly described and claimed in my aforementioned co-pending U. S. application, Serial No. 414,007.

With the foregoing in mind, the coupling means of the present invention contemplates the provision of a socket 20 or 20' in the enlarged or upper end of the body portion 14 or 14' or more strictly speaking, the base of the cone shaped body thereof. This socket 20 or 20' is formed to accommodate the drive lug 11 or 11' and therefore the drive lug will be explained first.

Referring to Figs. 1, 3, 4 and 5, the lug 11 is a key-like fitting having a plate-like formation 21 on its upper face formed integrally with a lower key portion 22. This plate-like formation is preferably confined to a shape within the mean diameter of the base of the cone shaped body 14 of the pilot bit 12 as well as that of the drill shaft 13. Thus the joint between these three elements, namely the pilot bit, the lug and the drive shaft, is relatively straight and uniform with no projections therefrom.

The key portion 22 of the lug 11 as best seen in Figs. 3 and 5 is adapted to be coaxially disposed with respect to pilot bit and drive shaft. To this end the key portion 22 of the lug is symmetrical in plan as illustrated in Fig. 5, and relative to the axis A about which the drive lug turns. In plan, the key portion extends substantially diametrically across the mean diameter of the plate-like formation 21 at the upper end of the lug.

In accordance with the present invention, the diametrical key portion 22 is provided with a twist in the direction of rotation of the pilot bit for reasons more particularly explained later in connection with the pilot bit. The lug 22 also includes a pair of lateral ears 23 and 24 on either side of the diametrical key but in a leading direction thereon relative to a line transverse to the diametrical key 22, and in relation to the direction of rotation thereof. These ears 23, 24 are formed integrally with the key portion 22 as well as the upper disc portion 21 as will be clearly seen in Figs. 1, 3, 4 and 7.

The ears 23, 24 extend downwardly only partly the depth of the key portion 22, the extent of the depth

of the ears being limited only by the girth of the central body portion 14 or 14' of the pilot bit. In other words, the limitation occasioned by the ability of the central body of the pilot bit to provide for the socket 20 to receive both ears 23, 24 as well as the diametrical key portion 22.

The lower extremity of the key portion 22 is provided with an eye portion 25, a relatively U-shaped appendage 26 having its legs 27 and 28 formed integrally with and depending from the lower edge of the key portion 22. This leaves an opening 29 in the eye portion for the receipt of a bolt or pin 30 for securing the pilot bit to the drive lug 11.

Referring now more particularly to the pilot bit 12 or 12', the form of which may be any desired design provided it has a central body portion 14 or 14' suitable for the receipt of the drive lug 11 or 11' in a manner now to be explained. The pilot bit 12 or 12' has diametrically opposed spiral blades 31 and 32 which extend radially (in plan section) from the cone-like central body portion 14 or 14' as the case may be. It is along a diametrical line extending from blade to blade that the socket 20 is formed to receive the diametrical key portion 22. This is clearly illustrated in Figs. 2 and 5 wherein it will be noted that the extremities of the key portion 22 extend partially into the body of the blades at their zone of joinder with central body portion 14 or 14'. Since each blade 31, 32 is formed concave on its leading face and convex on its trailing face, the substantially diametric socket 20 has a slight twist conforming to the contour of a transverse section through the blades. This assures sufficient body between the walls of the socket and the exterior surface of the pilot bit as is well illustrated in Fig. 5. In addition to the foregoing, and as depicted in Fig. 2, a partial recess or well 33, 34 is provided adjacent the socket 20 to accommodate the ears 23, 24, respectively, which extend from either side of the key portion 22 of the lug.

The socket 20 extends downwardly into the main or central body of the pilot bit sufficiently to receive the key portion 22 of the lug 11. At this zone of the main body 14 or 14', the latter's taper or conical shape limits the depth of the socket at the full width of the key 22. Thus at this zone the socket narrows down to a recess 35 configurated to receive the eye portion 25 as best seen in Figs. 4 and 8. Moreover, since the eye portions 25 and 25' are narrower than the key portion 22 of the drive lug (Figs. 3 and 7) each recess 35 and 35' can also be narrowed down in a direction transverse to the diametrical key 22 as best seen in Figs. 2 and 7, respectively. For this reason the cone like body 14 or 14' can be recessed somewhat from the outer sides to provide vertical walls 36' and 37' on either side of the eye portion 25' as is clearly illustrated in Fig. 7 only. It is at this plane or zone that the cone-like body is provided with a bore 38 for the receipt of the pin or bolt 30 by which the drive lug is secured to the pilot bit.

Referring now to Figs. 2, 5 and 6, it should be understood that the pilot bit 12 or 12' is to be driven in a clockwise direction about axis A as depicted in these views. As previously explained in connection with the drive lug it will be remembered that the latter is provided with ears 23, 24 which are in a leading direction relative to the direction of rotation thereof. The theory of this construction is diagrammatically illustrated by the force arrows f within the socket 20 as depicted in Fig. 5, wherein the entire assembly turns about the axis A in the direction of arcuate arrow a . Force arrows f^1 illustrate the leading faces of the two ends of the key portion 22 bearing against the adjacent complementary walls of the socket 20. Force arrows f^2 illustrate the leading faces of the two ears 23, 24 bearing against the adjacent complementary walls of the side wells 33, 34. With the ears 23 and 24 on opposite sides of the diametrically extend-

ing key 22 a forward thrust in the direction of arrows f^2 on these ears supplements the thrust in the direction of arrows f^1 at the extremities of the key 22. Since the total force required to turn the pilot bit is divided between the extremities of the key 22 and the two side ears 5 it will be appreciated that the amount of force required at the extremities of the diametrically extending key is appreciably lessened. In other words the total force is distributed between the leading faces of all four major 10 projections on the drive lug. Consequently it may be said that the amount of force required at the extremities of the diametrically extending key portion is appreciably less than it would be if the two ears 23 and 24 were not employed. To put it another way, the two ears 23 and 15 24 in effect minimize the counterforces or resistance to the forces at say arrows f^1 on the leading faces at the two ends of the diametrically extending key portion 22.

In addition to the foregoing, since the ears 23, 24 are 20 each disposed in advance of a line transverse to the diametrically extending key 22 they each exert a force (f^2) directly behind the respective extremities (driving ends) of the key 22. Moreover, the key 22 is materially reinforced at a critical zone, i. e., directly behind each 25 forwardly moving half of the diametrically extending key.

As seen in Fig. 5, the forces f^1 exerted by the leading 30 faces of the extremities of the key 22 are transmitted toward the leading faces of the respective blades 31 and 32. It will also be noted that the forces f^2 on each ear 23, 24 are directed against the heel end of each blade 31, 32 exerting a driving force axially outward thereof.

The foregoing theory of drive connection is equally 35 true with respect to the form of drive connection between the lug 11' and pilot bit 12' shown in Figs. 6 through 9. The only difference between the form in Figs. 1 through 5 and the form in Figs. 6 through 9 resides in the provision of a system of passages P in the latter form for the admission of air, fluid or other such clearing media to the bore being made by the pilot bit 12'.

In connection with the foregoing, it will be seen (Fig. 40 7) that the drill shaft 13' is provided with a central bore B communicable at its upper end with a source of fluid supply (not shown). This may be accomplished in any usual or well known manner by a hydraulic pump or 45 compressed air apparatus whichever is desired. It is contemplated that the fluid supplied via the bore B shall be distributed equally to either side of the pilot bit, i. e., to a zone to the rear of each blade 31', 32' thereon for distribution into the zone of cutting of the leading end of each blade at the tip of the pilot bit. To this end the 50 pilot bit 12' is provided with exit ports 40 and 41 each communicating with the lowermost extremity of the socket 20', i. e., the recess 35' thereof as depicted in Figs. 7, 8 and 9. It will thus be appreciated that the socket 20' itself becomes a part of the passage system 55 P by which the fluid is conveyed. This is so because as noted in Fig. 5 there is a clearance space between the trailing face of each key portion 22 and the wall of the recess 20 behind it. There is also a clearance space between the trailing face of each of the ears 23-24 and the wall of the respective recess 33 and 34 behind them. These clearances are also provided in the unit of Figs. 6, 7 and 8 although the parts are designated with prime numerals 20', 22', 23', 24', 33' and 34', respectively. In addition to the foregoing, it will be noted in Fig. 8 60 that the recess 35' is flared outwardly at its upper open end to merge with the end walls of the diametrical recess 20'. Moreover as seen in Fig. 7 part of the central body 14' of the pilot bit is removed to the rear of the side wells 33', 34' where the ears 23', 24' seat. The removal of such portion of the central body portion in a zone where little or no bearing occurs between the drive lug and the pilot bit does not weaken the latter and serves to complete the passage system P to a point to the rear of each 65 of the ears 23', 24' on the lug 11'. Here the lug 11' is

provided with exit ports 43, 44 at the terminal ends of bifurcated passages 45, 46 which converge with the bore B in the drive shaft 13'.

Since the provision of bifurcated passages, such as the ones 45 and 46 above explained, would not ordinarily occur in a common bored drive shaft, it is proposed that the drive lug 11' be welded to a specially built length or stud of shafting 47' preformed in the manner described. The upper end of the stud 47' could be welded in alignment with the drill shaft 13' or, as illustrated in Fig. 7 can be secured to the latter by threaded connection.

So far as concerns the mode of connecting the drive lug to any form of drill shaft, a short cap such as the one 47 shown in Fig. 1 may be employed. In this form the upper plate-like formation 21 of the lug is welded to the bottom of the cap 47. It should be apparent that the disc formation 21 may also be connected directly to the drill shaft 13 as by welding in the manner illustrated in Fig. 4.

Referring now to the lug illustrated in Figs. 10 and 11, the same may be constructed as explained in connection with either Figs. 1 through 5 or Figs. 6 through 9. The main distinction in the lug of Figs. 10 and 11 resides in the provision of a lateral or radial extension 50 on the plate-like formation 21 thereof to fill up the gap between the lower end of the helical blade H on the drill shaft (or auger) and the upper end of one of the blades 31 or 32 on the pilot bit 12 or 12'.

Thus it will be seen in Figs. 10 and 11 that the upper disc formation of either form of drive lug 11 or 11' when provided with the lateral arm 50 may be welded directly to the lower end of an auger shaft, the arm 50 being simultaneously welded to the lower terminal end of the helical blade H thereof. Now then the auger thus supplied with the lug is adapted to be coupled to a pilot bit in the same manner as described above with assurance that at least one of the blades 31 or 32 of the pilot bit will be in register with the helical blade H of the auger. Of course it will be understood that should the auger be provided with double helix blades each of the latter may be secured to lateral arms 50, the lug being provided with two such arms. In this case both blades 31 and 32 of the pilot bit will be registered (by the key-like lug) with the double helix blades of the auger.

While I have illustrated and described a preferred embodiment of the present invention, it will be understood however, that various changes and modifications may be made in the details thereof without departing from the spirit and scope of the invention as set forth in the appended claims.

Having thus described the invention, what I claim as new and desire to protect by Letters Patent is defined in the following claims.

I claim:

1. In combination with a pilot bit of the type having dual helical blades formed integrally with a relatively cone-shaped central body portion, means for coupling said pilot bit to a drive shaft comprising a drive lug having a plate-like formation secured to the end of said drive shaft, said lug comprising a depending key portion formed integrally with said plate-like formation and an ear disposed perpendicular to said key portion on either side thereof, said key portion spanning the full diameter of said plate-like formation between the dual blades of said pilot bit and twisting congruent to the helical trend thereof to a depth limited by the ability of the cone-shaped central body of said pilot bit to receive the same, said cone shaped central body having a socket formed therein complementary to said diametrically extending key portion for receiving the same, said ears between said plate formation and key portion each being disposed in a leading direction relative to the direction of turning of said drive shaft for transmitting direct driving forces to said pilot bit and for minimizing counterforces of the latter against said key portion, and a bolt extending through

said key portion and the cone shaped central body of said pilot bit for attaching the latter to said drive lug.

2. In combination with a pilot bit of the type having dual helical blades formed integrally with a relatively cone-shaped central body portion, means for coupling said pilot bit to a drive shaft comprising a drive lug having a plate-like formation secured to the end of said drive shaft, said drive lug comprising a depending diametrical key portion formed integrally with said plate-like formation and extending the full diameter of the same to a depth limited by the ability of said cone-shaped central body of said pilot bit to receive the same, said cone shaped central body having a socket formed therein complementary to said key portion for receiving the same, said socket extending diametrically between the dual helical blades of said pilot bit and tending in a helical twist congruent to the helix of said blades, said key portion being twisted in conformity with the helical twist in said socket, and an ear formed between said plate formation and key portion on each side of the latter, each said ear being disposed in a leading direction relative to a line transverse to said key portion and in relation to the direction of turning of said drive shaft for transmitting direct driving forces to said pilot bit and for minimizing counterforces of the latter against said key portion, and a bolt extending through said key portion and the cone-shaped central body of said pilot bit for attaching the latter to said drive lug.

3. Coupling means between a drive shaft and a pilot bit comprising a drive lug having its upper end secured to the lower end of said drive shaft, a diametrically extending key portion formed integrally with the upper end of said drive lug and depending therefrom, an ear formed on either side of said key portion and each disposed in a leading direction relative to a line transverse to the diametrically extending key portion and with respect to the direction of turning of said drive shaft, said pilot bit having a solid central body portion the upper end of which conforms substantially to the upper end of said drive lug for abutting relation therewith and provided with a diametrical socket complementary to said key portion for receiving the same, a shelf-like recess formed in the central body portion of said pilot bit on either side of the socket therein complementary to said ears for receiving said ears, and a bolt extending through said pilot bit and said key portion for securing said pilot bit to said drive lug.

4. Coupling means between a drive shaft and a pilot bit comprising a drive lug having a plate-like formation confined within the diameter of the lower end of said drive shaft, means for securing the plate-like formation of said lug to the lower end of said drive shaft, a diametrically extending key portion formed integrally with said plate-like formation and depending therefrom, an ear formed on each side of said key portion and integrally with said plate-like formation, each said ear being disposed in a leading direction with respect to a line transverse to said diametric key and relative to the direction of turning of said drive shaft, said pilot bit having a solid central body portion the upper end of which conforms substantially to the plate-like formation of said lug for abutting relation therewith, the central body portion of said pilot bit being provided with a diametrical socket complementary to said key portion for receiving the same, a pair of shelf-like recesses formed in said central body portion, one on either side of said socket in conformity with the disposition of the ears on said lug for receiving said pair of ears, said key portion having an eye formed therethrough transversely thereof, said solid central body portion of the pilot bit having aligned bores formed therethrough in register with the eye formed through said key portion, and a bolt extending through said aligned bores and the eye formed in said key portion for securing said pilot bit to said drive lug.

5. Coupling means between a helically bladed auger shaft and a pilot bit having a helical blade comprising a drive lug having a plate-like formation secured to the lower end of said auger shaft, a key portion formed integrally with and diametrically across said plate-like formation and depending therefrom, an ear formed on each side of said key portion, each said ear being disposed in a leading direction with respect to a line transverse to said key portion and in the direction of turning of said auger shaft, said pilot bit having a solid central body portion the upper end of which conforms substantially to the plate-like formation of said lug for abutting relation therewith, the central body portion of said pilot bit being provided with a diametrical socket complementary to said key portion for receiving the same, a pair of shelf-like recesses formed in the central body portion of said pilot bit on either side of said socket complementary to said ears for receiving said pair of ears, a pin extending through said pilot bit and said key portion for securing said pilot bit to said drive lug, and a lateral arm formed integrally with the plate-like formation of said lug in a position to register with the helical blade of said auger and the helical blade of said pilot bit.

6. In a coupling means between a bored drive shaft and a pilot bit having helical blades provided with passages exiting on the trailing side of each of said helical blades, a drive lug having a plate-like formation secured to the lower end of said drive shaft and provided with diverging passages converging at the plane of register with the bores in said drive shaft, a key portion formed integrally with said plate-like formation and depending therefrom diametrically thereof, a pair of ears formed integrally with said plate-like formation and said key portion so as to extend laterally from each side of said key portion in a leading direction relative to a line transverse to said diametrically extending key portion with respect to the direction of turning of said drive shaft and ahead of the outlets of the diverging passages in said plate-like formation, said pilot bit having a solid central body portion the upper end of which conforms substantially to said plate-like formation for abutting relation therewith, the central body of said pilot bit being provided with a diametrically disposed socket to receive said key portion and having a pair of shelf-like recesses on either side of said socket complementary to the ears on either side of said key portion for receiving the ears, said key portion and said ears leaving a clearance space between their trailing faces and the respective adjacent wall of said socket and recesses behind them for communicating the outlets of the diverging passages in said plate-like formation with the base of said socket, the base of said socket having communication with the passages exiting on the trailing side of each of said helical blades, and a bolt extending through said pilot bit and said key portion for attaching said pilot bit to said drive lug.

7. In combination with a pilot bit of the type having diametric helical blades formed integrally with a relatively cone-shaped central body portion, means for coupling said pilot bit to a drive shaft comprising a drive lug having a plate-like formation secured to the end of said drive shaft, said drive lug having a depending key portion formed integrally with said plate-like formation and extending the full diameter of the same and to a depth limited by the ability of said cone-shaped central body of said pilot bit to receive the same, said cone-shaped central body having a socket formed therein complementary to said key portion for receiving the same and having a pair of shelf-like recesses formed in said central body, one on either side of said socket and each in advance of a line

transverse to said socket and in relation to the direction of turning of said pilot bit, a pair of ears formed integrally with and between said plate-like formation and key portion, each said ear being disposed in a leading direction on either side of said key portion and relative to the direction of turning of said drive shaft for transmitting direct driving forces from said drive lug to said pilot bit and for minimizing counterforces of the latter against said key portion, and a bolt extending through said key portion and the cone-shaped central body of said pilot bit for attaching the latter to said drive lug.

8. In combination with a pilot bit of the type having dual helical blades formed integrally with a relatively cone-shaped central body portion, means for coupling said pilot bit to a drive shaft comprising a drive lug having a plate-like formation secured to the end of said drive shaft, said drive lug comprising a depending diametrical key portion formed integrally with said plate-like formation and flanked at each of its sides by an ear portion, said cone-shaped central body having a socket formed therein complementary to said key and ear portions for receiving the same, said pair of ears being formed between said plate-like formation and key portion in a leading direction relative to a line transverse to said diametrical key portion and the direction of turning of said drive shaft for transmitting direct driving forces to said pilot bit and for minimizing counterforces of the latter against said key portion, said key portion having an eye formed therethrough transversely thereof, said solid central portion of the pilot bit having aligned bores formed therethrough in register with the eye formed through said key portion, and a bolt extending through said aligned bores and the eye formed in said key portion for securing said pilot bit to said drive lug.

9. The combination with a pilot bit of the type having diametric helical blades formed integrally with a relatively cone-shaped central body portion and a drive shaft having an axial bore, of means for coupling said pilot bit to said drive shaft comprising a drive lug having a plate-like formation secured to the end of said drive shaft, said drive lug comprising a depending key portion formed integrally with said plate-like formation and a pair of ears formed integrally with and between said plate formation and key portion, each said ear being disposed in a leading direction relative to a line transverse to said key portion and the direction of turning of said drive shaft, said cone-shaped body of said pilot bit having a socket formed therein complementary to said key portion and said pair of ears for receiving the same, and a pair of exit passages formed through the sides of said cone-shaped body in communication with said socket therein and exiting on the rearmost face of each of said helical blades of said pilot bit, and said drive lug having an inlet port in register with the bore in said drive shaft and having two passages diverging therefrom for exit to the rearmost side of each of said ears whereby fluid discharged from the bore of said drive shaft is transmitted through said socket for exit therefrom via the exit passages through said helical blades, and a bolt extending through said pilot bit and said key portion for attaching said pilot bit to said drive lug.
